FURNACE

Donald J. Luty, Detroit, Mich., assignor to Wood
Hydraulic Hoist & Body Company, Detroit,
Mich., a corporation of Michigan

Application March 17, 1933, Serial No. 661,256

16 Claims. (Cl. 110—49)

This invention relates to recirculation control of burned gas in producing combustion. The invention is especially applicable to oil burners, and particularly to oil burners used to heat furnaces although it is conceived that the use and control of burned gases of combustion recirculated to the flame may be useful in other flames than oil burners.

In the burning of oil for fuel in furnaces or boilers it is necessary to provide air to be mixed with the oil so that combustion can occur and it has been found that use of burned gases from the combustion, circulated and controlled and mixed with the combustible mixture has many advantages. Mixing burned gas with the oil and air in the combustible mixture has the result of enlarging the flame and reducing its temperature. Such a flame is termed a blue flame as distinguished from the luminous flame which occurs when the combustible mixture consists only of oil and fresh air. This blue flame, burning in the presence of a forced current of air mixed with burned gas, burns with substantially no noise whereas the luminous flame produces a considerable noise in its combustion which has been greatly objectionable when used in a home heating equipment.

Because the blue flame is of greater size than the luminous flame its heat is distributed over a greater area within the combustion chamber which has the desirable result of even heat distribution. The blue flame is of lower temperature than the luminous flame which considerably reduces the deterioration of the walls of the combustion chamber in which it burns and permits the practical use of a metal combustion chamber. Although the blue flame is of lower temperature, the fact that it is of greater size than the luminous flame causes it to produce the same amount of aggregate heat as the luminous flame with the same amount of fuel consumed. The blue flame also largely eliminates carbon deposit within the furnace owing to the fact that no free carbon is produced in the process of combustion. This fact is attested by the absence of luminosity ordinarily produced by free carbon rendered incandescent by the heat of combustion.

The blue flame is produced by mixing with the air and oil a controlled quantity of gas having no oxygen or a low oxygen content which may be conveniently obtained in the form of the burned gases of combustion from the flame which are recirculated from the gas flues of the furnace back into the combustion chamber, preferably by the

same means as is used to produce the fresh air current. The flame can only burn in the presence of a predetermined proportion of burned gas in the mixture and if an excess amount of burned gas is used the flame will expire and therefore, if it is desired to mix a considerable quantity of burned gas with the combustible mixture the quantity of burned gas with the combustible mixture the quantity must be carefully controlled to prevent the flame from being extinguished.

Inasmuch as the burned gas is obtained from the gas flues of the furnace which are subject to various degrees of pressure, both above and below atmospheric pressure, it is evident that a mere fixed orifice to admit the recirculated gas from the gas flues to the combustion chamber will not suffice and that automatic means must be provided which will compensate for the variations in pressure in the gas flues.

This invention provides means for automatically maintaining a predetermined proportion of air and burned gas supplied to the combustion chamber and mixed with oil under normal combustion conditions. It also provides means to prevent an excess amount of burned gas being supplied under abnormal conditions. It also provides means for supplying air without burned gas at, and shortly following, the instant of ignition which assures ignition taking place and combustion being established. The invention provides various means of adjustment to compensate for varying draft conditions and other variable conditions and also provides various other new and useful features of construction and arrangement as hereinafter more fully described and particularly pointed out in the claims, reference being had to the accompanying drawings, in which,

Fig. 1 is a longitudinal vertical section through a boiler equipped with this invention, the attachment forming the control mechanism of my invention being shown in elevation.

Fig. 2 is a front elevation of the boiler shown in Fig. 1, parts being broken away and in section for better disclosure.

Fig. 3 is a fragmentary enlarged vertical section through the air inlet and combustion gas conduit leading to the motor driven fan which forces the mixture of air and gases of combustion into the combustion chamber.

Fig. 4 is an elevation of the lower portion of the combustion gas conduit, partially in section, showing the weighted lever on the gas vane shaft fixed in one position for one result, and

Fig. 5 shows the same parts with the weighted

lever fixed in another position for a different result.

Like reference characters refer to like parts in the different figures of the drawings.

5 The heat unit, indicated at 1, is a boiler having an inner horizontal combustion chamber 2 where the fuel is burned, from which down draft passages 3 for the products of combustion extend vertically between cross conduits 4 in which 10 is water, the products of combustion passing to a horizontal flue 5, from which part of the same may pass outwardly through a smoke pipe 6. This construction in general is like that shown in the patent to Jerome No. 1,804,777, issued 15 May 12, 1931 for Boiler, reissued April 17, 1934, No. 19,138 with which my invention is here shown associated; though it is to be understood that the invention is in no sense limited to any specific type of boiler or water heating plant, but 20 may be utilized quite as well with other types of boilers or with hot air furnaces and the like.

The fuel, which is of a hydrocarbon composition, is pumped to a mixing chamber at the entrance of the combustion chamber through 25 a pipe 7 passing through a larger passage 8 in a conduit 9 which joins with a housing 10 at the upper end of a vertical conduit 11 which, at its lower end, connects with a fan housing 12. An electric motor 13 has a rotary fan 14 on its 30 shaft 13a within the housing 12 for forcing and blowing air, and as will hereafter appear, some of the gaseous products of combustion are drawn from the flue 5 to be mixed with air and fuel to provide a combustible mixture which burns 35 in the combustion chamber 2.

The conduit for air and the recirculated portion of the gaseous products of combustion is a vertical pipe 15, the upper end of which has an outlet 16 around the shaft 13a of the motor 40 to lead into the interior of the fan housing 12. At its lower end the pipe conduit 15 is formed with a rectangular box 15a, which is connected by a pipe or conduit 17 with one end of the flue 5 previously described, from the other end 45 of which the smoke pipe 6 extends.

In a side of the conduit 15 an air opening 18 is made. In the lower part 15a a vane 19 is suspended from a rock shaft 20. The vane 19 is rectangular and its top and vertical edges 50 lie close to the adjacent sides of the box 15a to prevent substantial passage of gas while its lower edge is spaced from the bottom of the box. At one outer end of the shaft 20 a lever 21, having a weight 22 adjustably mounted thereon, 55 is located, the lever being mounted for rotatable adjustment on the shaft for purposes hereafter described.

Supporting rods 23 are rigidly connected at their lower ends to the vane 19 and at their 60 upper ends pass through the opening 18 and carry a closure plate or air valve 24 slightly longer and also wider than the opening 18. Adjustable stop screws 25 are mounted on and extend through the pipe 15, having their ends 65 located so that the plate 24 comes thereagainst in the position of the parts shown in Fig. 3, which prevents complete closure of the air opening 18.

Gas passes from the pipe 17 under the lower 70 edge of the vane 19 and is metered by the space between the lower edge of the vane and the adjustable plate 26. The plate 26 is hinged at 27 to the forward side of the box 15a, the hinge being located so that the lower edge of the vane 19, when swung sufficiently, will engage it to

completely close the opening under the vane. The plate inclines downwardly and may have its movable edge rest against the bottom of the box 15a or its inclination may be altered by raising its movable edge by means of adjusting screws 28 whereby the passage space under the vane 19 may be altered. By this construction a gradual variation of the gas passage occurs by swinging the vane 19, which passage varies from extreme opening when the vane is swung rearwardly toward the pipe 17 to a complete closure when the vane is swung forwardly against the hinge 27.

Fuel is furnished to the fuel feed pipe 7 by a fuel pump 30 which is located on the outside 1 of the conduit 15 and the shaft 13a, which is driven by the motor 13 and carries the fan rotor 14, also operates the fuel pump 30. By this means the supply of fuel is automatically provided whenever the motor 13 and the fan 14 2 are in operation and cessation of the operation of these parts automatically stops the feeding of fuel.

Operation

2 While in operation the motor 13 drives the fan 14 which blows air, taken through the opening 18, mixed with the products of combustion taken from the flue 5 through the pipe 17 and passing under the vane 19, which mixture is blown 3 through the conduit 11, the housing 10 and pipe 9 into the combustion chamber where it mixes with fuel supplied by the pipe 7 providing a combustible mixture which is ignited by suitable means and burns within the combustion chamber 3.

2. The gaseous products of this combustion pass off, in the particular furnace structure shown, through the downward passages 3 into the flue 5, the smoke pipe 6 connecting with said flue 5 through which a part of the burned gas 4 passes to a chimney and a part of the gas from the flue 5 is drawn, as above described, through the pipe 17 and the other parts by the fan 14 to be mixed with air and reburned.

It is most desirable for even, quiet and safe 4 combustion to maintain a constant substantially fixed proportion of fresh air and burned gas during normal operating conditions and this proportion is effectively maintained by operation of the present device. The suction produced by 5 the fan 14, when it is in full motion, is constant and the pressure of the fresh air causing it to pass through the opening 18 is also constant but the pressure of the burned gas in the flue 5 varies greatly because of the different forces acting 5 upon it.

The draft in the chimney, to which the smoke pipe 6 is connected, will vary because of outside 6 weather conditions including temperatures, wind conditions, humidity, etc., and the heat of the chimney and smoke pipe will also have its effect upon the draft created. Fluctuations in the flame, called flame pulsations, decidedly affect the pressure in the flue 5 and other forces may act to alter the pressure in the flue.

The vane 19 controls the quantity of burned 7 gas drawn from the flue 5 by the fan 14, this gas passing under the vane and between its lower edge and the plate 26 and the opening between the vane and the plate 26 controls the quantity of gas permitted to pass. The suction produced by the fan acts upon the vane 19 tending to swing it toward the hinge stop 27 such movement being resisted by the weight 22, and suction within the flue 5 acts oppositely upon the vane to move it 7.

in the other direction, such action being aided by the weight 22.

With a constant suction produced by the fan, the variable suction or pressure in the flue 5 causes a movement of the vane to control the passage of gas past it. The condition of the gas in the flue 5 may be termed as pressure with the understanding that such pressure may be either greater or less than atmospheric pressure depending upon the draft existing in the chimney and smoke pipe 6. Under certain conditions, especially when the chimney and smoke pipe are cold, substantially no draft will exist and pressure created in the combustion chamber 2 will be transmitted to the flue 5 causing a pressure above atmospheric in said flue while at other times when a relatively strong draft exists the pressure within the flue 5 will be less than atmospheric pressure.

With a high pressure in the flue 5 the fan would ordinarily draw an excessive amount of burned gas to be mixed with the air for combustion but such pressure in the flue acts upon the vane 19, in conjunction with the suction of the fan acting upon the vane, causing the vane to move toward the stop 27 to reduce the size of the passage. A low pressure in the flue 5 has the natural effect to resist movement caused by suction of the fan but this same effort acts upon the vane 19 causing it to move farther from the stop 27 increasing the opening and permitting an easier passage of the gas. With a high pressure in the flue 5 and the passage past the vane restricted the flow of gas will be more rapid through the restricted passage and with a low pressure in the flue and the passage opening past the vane increased the gas will flow through the increased passage at a lower speed.

Fluctuation of the vane 19 causes corresponding fluctuation of the closure plate 24 at the fresh air opening 18, movement of the plate 24 being in a direction to provide a larger opening for the passage of air with movement of the vane 19 in a direction to restrict the size of the gas passageway.

The device is adjusted for operation by determining the average normal positions of the air valve 24 and the gas vane 19 under draft conditions existing in that particular installation and the stop screw 25 is moved to a position to engage the valve plate 24 when it has moved toward closed position somewhat beyond the average normal position. The lever 21, with its weight 22, is rotatably adjusted on the shaft 20 so that it will exert the proper effort required in that particular installation to resist closing movement of the vane.

It will be noted that when the lever 21 is adjusted on the shaft 20 to stand in a substantially horizontal position, as shown in Fig. 3, the effort of the weight 22 to swing the vane 19 is substantially constant throughout the arc in which it moves. If the lever 21 is adjusted on the shaft 20 to extend downwardly as in Fig. 5 the effort of the weight to resist closing movement of the vane increases as the vane swings toward closed position while if the lever is adjusted on the shaft to extend upwardly as shown in Fig. 4, the effort of the weight to resist closing movement of the vane decreases as the vane moves toward closed position. Adjustment of the weight 22 lengthwise of the lever 21 governs the amount of effort exerted in any of the positions of the lever.

The plate 26 is adjusted by the screws 28 to

govern the maximum gas passage between it and the lower edge of the vane 19. This plate extends tangentially from the arc in which the lower edge of the vane swings and therefore movement of the vane toward the point of convergence between its arc and the plate reduces the distance between the lower edge of the vane and the plate.

With the parts properly adjusted a substantially constant proportion of air through the opening 18 and burned gas through the pipe 17 is supplied by the fan 12 to the combustion chamber where it is mixed with fuel oil from the pipe 7 to be burned. Under normal conditions the vane 19 is affected by change in pressure in the gas flue 5 causing it to swing from one position to another increasing or decreasing the gas passage beneath its lower edge and at the same time moving the plate 24 and inversely varying the air passage through the opening 18.

These parts are so proportioned and adjusted that they will maintain a substantially constant proportion of burned gas and air during normal running conditions and will not permit the passage of gas in sufficient quantity to extinguish the flame. In cases of abnormal gas flue pressure, which can be caused by extreme flame pulsations or other causes, the vane 19 moves against the hinge stop 27 completely closing the gas passage and opening the air passage to its fullest extent whereby only fresh air is admitted to the flame which will cause it for the instant during such abnormal pressure to become luminous which is the safest burning condition.

Since this apparatus is especially adapted to be used in automatic thermostatically controlled oil burning furnaces in which combustion occurs at intermittent intervals and in which there are frequent ignition periods, the device is arranged to facilitate the ignition of the fuel at each ignition period. After the flame has been extinguished for some time the gas flues and combustion chamber of the furnace will have exhausted all of the burned gas therein into the smoke stack and will contain substantially fresh air. Therefore at the time of ignition only fresh air can be supplied to the fuel which provides the best mixture to assure ignition and fresh air continues to be supplied, both through the air opening 18 and past the vane 19 for an appreciable period until the burned gas of combustion has had time to circulate from the combustion chamber through the gas passages and back to the flame which period is sufficiently long to assure establishment of combustion. As soon as burned gas from the combustion chamber has circulated through the gas flues so that it can pass the vane 19 to be mixed with air in the conduit 15 and supplied to the fire, the flame assumes a blue condition and the device automatically acts to maintain this condition under normal conditions until the flame is extinguished.

Although the invention has been heretofore described in its most complete aspect it is conceived that the vane 19, or an analogous member, moved by differences in draft pressure may be utilized to automatically govern the fresh air supply valve without passage of burned gas to be introduced into the fire. It is also conceived that the automatic control of the recirculation of burned gas to the fire actuated by differences in draft pressure may be utilized without the simultaneous variation of the fresh air supply.

The invention is defined in the appended claims.

and is to be considered comprehensive of all forms of structure coming within their scope.

I claim:

- 5 1. The combination with a furnace having a combustion chamber and a flue connected with a smoke pipe in all of which varying pressure occurs and to which gases of combustion are delivered, of a conduit communicating with said combustion chamber, means for forcing an air current in said conduit and into said combustion chamber, a communicating passage between said conduit and said burned gas flue, a movable valve member in the burned gas passage and affected by variations in pressure in said flue to be moved 15 toward either open or closed position, valve means for admitting fresh air into said conduit actuated by said gas valve means to be moved toward open position when the gas valve means moves toward closed position and vice versa.
- 20 2. The combination with a fuel burning combustion chamber having a horizontal flue to which gases of combustion are delivered and a smoke pipe connected with said flue, of a vertical conduit connected at its upper end with the front 25 part of said combustion chamber, a horizontal pipe connecting the lower end of said conduit with said flue, said vertical conduit having an air entrance opening in a vertical side thereof, a plate located at the outer side of said opening, a rod 30 connected to said plate, extending through said opening and downwardly adjacent said flue, a vane mounted to turn upon a horizontal axis mounted in said horizontal pipe adjacent the flue, the lower end of said rod being connected with 35 said vane and a blower in said conduit above said vane and air entrance opening.
3. A construction containing the elements in combination defined in claim 2, combined with means carried by said conduit to engage against 40 said plate to limit the extent of movement of said plate toward the conduit and thereby prevent complete closure of said air entrance opening.
4. In combination with a horizontal fuel burning combustion chamber, a horizontal flue below 45 said combustion chamber to which gaseous products of combustion are delivered, a smoke pipe connected to the flue, a vertical conduit having its upper end connected with the front end of the combustion chamber, said conduit having an air 50 entrance opening in a side thereof, a second pipe connecting the flue with the lower end of the conduit, a horizontal shaft mounted on and extending through the conduit a short distance in front of said last mentioned pipe, a vane attached to 55 and depending from said shaft, an arm connected to one outer end of the shaft, a weight adjustably mounted on said arm, a plate larger than the air entrance opening located at the outer side of the flue in a position to cover said opening, a rod 60 secured at one end to said plate and at the other end to said vane a short distance below said shaft, and a motor driven blower located in said conduit above said vane and air entrance opening.
5. A construction containing the elements in 65 combination defined in claim 4, combined with adjusting screws on the conduit and having ends bearing against the inner side of said plate.
6. A construction containing the elements in combination defined in claim 4 combined with 70 stop means located in the lower portion of said conduit opposite the lower portion of said vane, said stop means extending substantially across the full width of the conduit in the path of movement of the lower portion of the vane.
- 75 7. The combination with a furnace having a

combustion chamber, of means for mixing gases of combustion with air comprising, a conduit for carrying a portion of the gases of combustion back to the entrance of the combustion chamber, a blower in said conduit, said conduit having an air entrance opening, a closure for said opening, obstructing means across the conduit partially obstructing the passage of said gases of combustion, said obstructing means being movably mounted and automatically movable to different positions to permit the passage of a greater or less quantity of the gases of combustion, and connections between said obstructing means and air inlet closure means causing the same to move simultaneously.

8. A construction containing the elements in combination defined in claim 7, combined with means located in said conduit in cooperation with said obstructing means for limiting or prohibiting the passage of gases of combustion to said conduit on the obstructing means moving a predetermined distance in one direction under excess pressure of said gases of combustion.

9. The combination with a furnace having a combustion chamber, a smoke pipe and a flue therebetween, said flue being of unobstructed inner construction and carrying the gases of combustion, of means for supplying undiluted fresh air to said combustion chamber, means for supplying burned gas from said flue to said combustion chamber and means subjected to pressure in said flue and stack and actuated by variations thereof for maintaining substantially constant the proportions of air and burned gas supplied to said combustion chamber during normal operation.

10. The combination with a furnace having a combustion chamber and a flue connected with a smoke pipe to which gases of combustion are delivered from the combustion chamber, of a conduit, in which varying pressure occurs, in communication with said flue, means for forcing the contents of said conduit therefrom into said combustion chamber, valve means for admitting undiluted fresh air into said conduit, valve means for admitting gases of combustion into said conduit, means for operatively connecting the gas valve means to the air valve means, said last mentioned valve means being actuated by variations in pressure in said flue for automatically actuating said air valve means whereby a substantially constant proportion of fresh air and gas is admitted to said conduit.

11. The elements in combination defined in claim 10 combined with means for independently adjusting the gas valve means.

12. The elements in combination defined in claim 10 combined with adjustable means for limiting the closing of the air valve means.

13. The combination with a furnace having a combustion chamber and a flue to which gases of combustion are delivered, of a conduit connecting one end of said flue with the entrance end of the combustion chamber, a blower in said conduit, a vane movably mounted in the conduit across the same between said blower and flue to partly obstruct passage of gases of combustion to said blower, said conduit having an air entrance opening therein, a plate to open or close said opening, and connections between the vane and plate to automatically and simultaneously open said air entrance opening to a greater degree and limit the passage of gases of combustion to a correspondingly lesser degree.

14. The combination of elements as set forth

in claim 13 but also having a weight normally holding the vane in a predetermined position.

15. The combination with a furnace having a combustion chamber, a smoke pipe and flue means therebetween whereby varying pressure occurs in said flue means during operation of said combustion chamber, of a conduit leading from said flue means to the combustion chamber, valve means in said conduit controlling the passage of a portion of the products of combustion therethrough, said valve means being movable from an open position to a closed position, the

varying pressure progressively moving the valve means toward and from its closed position whereby a lesser or greater opening is afforded for the said portion of the products of combustion to pass thereby.

16. The combination of elements set forth in claim 15, in which means is provided to admit a supply of fresh air at atmospheric pressure to the conduit between the valve means and the combustion chamber.

10

DONALD J. LUTY.
